RACK FOR NEWSPAPERS AND MAGAZINES

Clement J. Koeferl, Dover, N. J.

Application June 5, 1950, Serial No. 166,253

1 Claim. (Cl. 211—50)

1

This invention relates to supports or racks, and more particularly to supports or racks for accumulating, stacking, and bundling newspapers and magazines, and has for one of its primary objects the provision of an improved and simplified device of this character.

For many years housewives have been confronted with the problem of what to do with used newspapers and magazines, and very often the used newspapers and magazines have been thrown in a corner of the cellar or back porch. This means of storing used newspapers and magazines has not only resulted in an unsightly pile, but has also created a real fire hazard that in numbers of cases have resulted in the destruction of the homes where the newspapers were improperly stored. Thus, one other important object of the present invention is to provide a new article of manufacture which will make it easy for a housewife to systematically and neatly accumulate, stack and bundle used newspapers and magazines as they are discarded.

Another important object of the present invention is to provide a new and improved article of manufacture that will be inexpensive and which will also be serviceable and useful to the housewife and other users.

It is also an object of this invention to provide a rack for newspapers and/or magazines of generally improved construction, whereby, the device will be simple, durable and inexpensive in construction, as well as convenient, practical, serviceable and efficient in its uses.

Other important objects of the invention will become apparent from the following description and appended claim.

For a more complete understanding of this invention, reference should be had to the accompanying drawings, in which:

Figure 1 is a perspective view of a first preferred type of support or rack embodying my invention;

Figure 2 is a reduced scale side elevational view of the rack or support illustrated in Figure 1 and showing how the rack or support may be opened for convenient bundling;

Figure 3 is a side elevational view of a modified form of the invention showing a rack or support for magazines and newspapers, dotted portions thereof indicating the manner in which the sides of the rack may be dropped to facilitate bundling, and removal of the bundled newspapers and magazines, and

Figure 4 is a sectional view taken on the line 4—4 of Figure 3, the cords and magazines having been removed.

Referring to the drawings, this invention is shown in one form in Figures 1 and 2 as applied to a rack or support for accumulating, storing, and bundling newspapers or magazines, in which numeral 10 in a general way indicates a bot-

2

tom panel, numeral 12 indicates a front panel, numeral 13 indicates a rear panel, and numeral 16 a top connector bar. The bottom panel 10 is constructed from a pair of spaced base members or runners 16—16', of which the lower portions are slightly beveled. The front ends of the runners 16 and 16' are connected by a superimposed spanner member 17 and the rear ends of the runners are connected by a spanner 17'. The right ends (Figure 1) of the spanners 17—17' are connected by a connector member 18 and the left ends of the spanners are connected by a connector member 18'. It will be understood that the connector members 18 and 18' rest directly upon and are secured by unshown means to the tops of the hereinbefore described runners 16 and 16' respectively. The spanner members 17 and 17' in addition to being connected by the connector members 18 and 18' are joined by a plurality, in this case three, of equally spaced horizontally extending dowel sticks 19. As shown, the ends of the dowel sticks are positioned in holes 21 that extend through the connector members 17—17'. However, it will be understood that the holes 21 do not necessarily have to extend through the connector members 17 and 17'.

The top face of the front connector member 17 is cut away as at 22—22 and thereby accommodates the lower leaf of a pair of hinges 23—23, which are secured to the spanner members 17 by wood screws, one of which is shown at 24. The upper leaf of each of the hinges is secured by a plurality of wood screws, of which one is shown at 26, to the lower face of a bottom bar 27 of the front panel 12. A corner post 28 is secured to and extends upwardly from each end of the bottom bar 27, and the upper ends of the two corner posts are joined by a horizontally extending top bar 29. The bottom bar 27 and the top bar 29, in addition to being joined by the two corner posts 28—28, are connected by a plurality, in this case three, of vertically extending dowel sticks 31—31—31. The ends of the dowel sticks 31 are positioned in holes 30 formed in the bottom and top bars 27 and 29 respectively. Reference to the drawings shows that the front panel 12 is made up of the bottom bar 27, the two corner posts 28—28, the top bar 29, and the three vertical dowel sticks 31—31—31.

The rear panel 13 is an exact duplicate of the front panel 12, and comprises a rear bottom bar 27', a pair of upstanding corner posts 28'—28', a rear top bar 29', and a plurality of dowel sticks 31'. The rear panel 13 is hinged to the rear spanner 17' by a pair of rear hinges 23'—23', that are duplicates of, and are installed in the same manner as the front hinges 23—23.

The rear top bar 29' is connected to the front top bar 29 by the top connector 14, hereinbefore mentioned. The rear end of the top con-

necter bar 14 is hinged to the longitudinal center of the top bar 29 by a hinge 32, which is held to the center of the bar 29' and to the end of the connector by a plurality of wood screws 33. The front end of the connector bar 14 is releasably held to the center of the front top bar 29 by a latch 34, pivoted to the center of the front bar 29 by a screw 36. The free end of the latch 34 is provided with a notch 37 that is devised to engage a keeper 38, which, as shown, is in the form of a wood screw driven into the front end of the connector 14.

When the rack of this invention is being used to accumulate discarded papers and magazines, a length of string or cord 39, comprising a bight portion 41 and two end portions 42 and 42', is placed as shown in the drawings. In other words, the end 42 of the cord 39 is placed over the top of the front top bar 29. The bight 41 of the cord 39 is placed down inside the rack as best seen in Figure 1, and the other end 42' of the cord 39 is placed over the rear top bar 29'.

As best seen in Figure 1, the top connector bar 14 has notches 44-44', at points near both of its ends, and these notches engage the top bars 29 and 29', thus adding to the rigidity of the rack.

The rack of this invention is used in the following manner. The cord 39 is placed as shown with the bight 41 extending all the way to the bottom of the rack. If desired, the ends 42-42' of the cord may be tied or otherwise secured to the top bar member 29 and 29'. With the rack empty the top connector bar 14 is secured to the front top bar 29 by means of the latch 34 and keeper 38. Then, as the newspapers and/or magazines are discarded, they are placed in the rack so that the cord 39 will extend below and on both sides thereof. When enough of the papers have been accumulated to form a proper size bundle the ends 42-42' of the cord 39 are brought together as at 46 (Figure 2) and tied into a knot as shown. Then the latch 34 is uncoupled, the top connector 14 hinged upwardly, and the front and rear side panels 12 and 13 hinged downwardly as shown in Figure 2. This permits for easy and safe removal of the now securely tied bundle of papers, the bundle being designated in Figure 2, by the numeral 47.

Figures 3 and 4 of the drawings show a second preferred embodiment of the invention, which has many details, duplicated from the rack shown in Figures 1 and 2. The rack of Figures 3 and 4 is devised for the separate accumulation of newspapers and magazines. The parts of the rack shown in Figures 3 and 4 which are duplicates of parts shown in Figures 1 and 2 are designated by numerals less than 100, and these parts will not be redescribed in complete detail. On the other hand the parts that bear numbers above 100 are specific to the rack shown in Figures 3 and 4. The main difference between the double rack of Figures 3 and 4 and the single rack of Figures 1 and 2, resides in the fact that in Figures 3 and 4 the runners 116, the bottom connector members 118-118', and the dowel sticks 119, are extended to accommodate installation of a central fixed panel designated generally by the numeral 150. The fixed panel 150 is a duplicate of the hinged panels 12 and 13, except that the fixed panel is not hinged, but is secured to the bottom connector members 118 by a pair of T-straps 151-151' that are held to the bottom connector 118 and to the post 128 of the panel 150 by a plurality of screws 152. It will of course be understood that the double rack has two top con-

nectors 14-14, two sets of hinges 32-32, two latches 34-34, and two keepers 38-38.

While the drawings only illustrate two types of racks for accumulating, storing and bundling newspapers and magazines, it will be appreciated that other types of racks are possible of construction. For example, a very convenient single rack may be made from the double rack shown in Figures 3 and 4 by omitting one side of the double rack. This would result in a single rack having one fixed side and one hinged side. In addition to this two or even three cords 39 may be used, the ends of the cords being secured to spaced portions of the top bars 29 and 29'. Other variations in the construction of racks are contemplated and may be made within the scope of this invention without avoiding the appended claim.

What I claim and desire to secure by United States Letters Patent is:

A rack for accumulating, stacking, and bundling newspapers or magazines comprising a bottom panel formed from a pair of runners, a pair of spanners connecting said runners, and a pair 25 of connector members connecting said spanners, said connector members resting on said runners, and a plurality of dowel sticks extending between the said spanners; a pair of parallel upstanding side panels, each side panel having a bottom bar, 30 a pair of upstanding corner posts, a top bar connecting the upper ends of said corner posts, and a plurality of dowel sticks connecting said bottom bar with said top bar; leaf-hinges each comprising, a first leaf secured to one of said spanners 35 and a second leaf secured to one of said bottom bars and a pivot pin connecting the first and second leafs of each of said hinges, the said pivot pin connection being located adjacent to the side of the bottom bar which is remote from the side 40 of the bottom bar which is adjacent to the other bottom bar, thereby providing a pair of upstanding side panels which hinge outwardly but not inwardly; a long slim connecting bar of which the longitudinal dimension is substantially equal 45 to one of the dimensions of the bottom panel and of which the longitudinal dimension is at least eight times any cross sectional dimension thereof, said long slim connector bar having both ends notched and having one end hinged to one of said top bars; a latch and keeper for releasably connecting the other end of said top connector bar to the other of said top bars; said top bars being adapted to support opposite ends of cord means 50 bars adjacent to said long slim connector bar, thereby affording a means for bundling said newspapers or magazines.
